UNITED STATES PATENT OFFICE.

EDOUARD ERNEST FERDINAND LE PARMENTIER, OF DIEPPE, FRANCE.

BARGE.

1,303,689.

Specification of Letters Patent. Patented May 13, 1919.

Application filed August 11, 1917. Serial No. 185,704.

To all whom it may concern:

Be it known that I, EDOUARD ERNEST FERDINAND LE PARMENTIER, a citizen of the Republic of France, residing in Dieppe, Seine Inférieure, France, have invented certain new and useful Improvements in Barges, of which the following is a specification.

The object of this invention is to provide a marine barge so constructed that it cannot 10 be sunk or capsized.

The essential features of construction are the particular shape which prevents the barge from capsizing, namely the cylindrical form of the holds and the conical form of the ends, 15 the external longitudinal ribs on the hull and the arrangements for hermetically closing the vessel to render it incapable of sinking.

An example of the construction is shown 20 in the accompanying drawings in which Figure 1 is a side elevation; Fig. 2 a cross section on line X—X of Fig. 1; Fig. 3 a plan; Fig. 4 a detail view drawn to an enlarged scale; Fig. 5 a plan of Fig. 4; Fig. 6 a view 25 similar to Fig. 1, but showing certain details, and Fig. 7 a cross section drawn to an enlarged scale on line X—X of Fig. 6.

The holds *a* are cylindrical and are extended at each end of the barge by conical 30 portions *b*. The hatchways *d* are adapted to be closed hermetically by covers *c*. *e* is the deck-house and *f* the fore-castle; *g* is the tiller of the rudder *h* and *i* is a breakwater having a cutwater prow.

As shown in Figs. 4 and 5, each hatch 35 cover *c* is operated by a small fixed crane *l* which raises the cover and turning in a step-bearing *m* deposits it on the deck as indicated at *c'*, or performs the reverse movement; by this means the covers can be 40 strictly centered when put in place.

All openings, wherever they be, namely in the deck-house *e*, fore-castle *f*, compartments *b* or holds *a*, may thus be hermetically closed 45 so that the barge cannot be submerged.

Stability is insured for all cargoes in bulk, whether solid or liquid, owing to the internal profile of the barge, which for all conditions of load gives a fixed and common position to 50 all the differential metacenters. This fixed position of the differential metacenters, placed at the center of the inside volume of the holds, is thus always situated above the center of gravity of the cargoes whatever 55 may be their volume, density and nature. In particular, for liquid cargoes, the metacen-

tric interior development is reduced to a point and this point, common to all interior levels and, at the same time, the point of support of the cargo, coincides with the differential metacenter; it follows that the center of gravity of the empty barge, being intentionally below this differential metacenter, the general center of gravity for each condition of load, whatever may be its nature, will always be below the differential metacenter, which is at the same time the metacenter of the external hull; hence $\rho - \alpha$ 60 is always sure to be positive.

The fore- and aft-parts of the barge are 70 juxtaposed truncated cones *b*, which, being surfaces capable of development, facilitate the construction.

As shown in the section Fig. 2, the ribs *n* 75 are on the outside of the hull so as to simplify the construction; they increase the rigidity and constitute keels for resisting rolling.

The barge need not necessarily be towed but may be self-propelled by machinery 80 provided for the purpose.

The cylindrical and conical shapes already mentioned may be modified externally—

(a) by the addition of longitudinal external ribs *n* (Fig. 7) which, in addition to 85 the function ascribed to them above, extend toward the ends *b* (the dotted lines *o'* of Fig. 6 represent the projections of the center lines *o* Fig. 7) so as to constitute floatboards for lifting the boat to the waves and 90 insuring stability of direction by directing the liquid streams.

(b) by the addition of stranding keels *p* of dimensions sufficient to receive fixed or 95 movable ballast *q*, in addition to that which may be accommodated in the conical compartments *f'*.

Two or more barges may be coupled rigidly side by side, tangentially or not, by means of a frame-work of tight sheet iron, 100 the barges having common fore- and aft-parts like those described.

The object of this arrangement is to use the properties above enumerated, and in particular the essential fact that the interior metacenters of the individual liquid cargoes coincide with the centers of volume of their holds. In consequence, the resultant of the actions of the total liquid cargo has its point of application in the horizontal 105 plane passing through the line of centers, whatever may be the levels of the individual 110

liquid cargoes and the inclination of the barge. The advantage of this is to insure to the barge an angle of static stability greater than 90° with any cargo, solid or liquid, and whatever its condition of load.

The position of the crane, as indicated in Fig. 5, is suitable for any kind of cover, but more particularly to one of circular form; for square covers as shown in Fig. 5, it may 10 be advantageous in certain cases to arrange the step-bearing m at the angle of the cover.

Having thus described my invention and the best means I know of carrying the same into practical effect, I claim:—

15. 1. A barge having a hull externally and internally cylindrical, with conical ends, and hollow stranding keels fastened exteriorly to the hull and containing ballast.
2. A barge having a hull externally and 20 internally cylindrical, with conical ends formed of successive conic frusta.

3. A barge having a hull externally and internally cylindrical, with conical ends formed of successive conic frusta of angles successively more obtuse.

25 4. A barge having a hull externally and internally cylindrical, with conical ends, and a deck-house having a cutwater prow surmounting the conical bow, and the hull having a forecastle compartment communicating with said deck-house.

5. A barge having a hull externally and internally cylindrical, with conical ends, and a rudder partly cut away to conform to the conical stern.

35 In witness whereof I have hereunto signed my name in the presence of two subscribing witnesses.

EDOUARD ERNEST FERDINAND LE PARMENTIER.
